(57) **CLAIM**

The ornamental design for a mobile phone cover, as shown and described.

DESCRIPTION

FIG. 1 is a perspective view of a mobile phone cover; FIG. 2 is a front view of the mobile phone cover of FIG. 1; FIG. 3 is a rear view of the mobile phone cover of FIG. 1; FIG. 4 is a left-side view of the mobile phone cover of FIG. 1; FIG. 5 is a right-side view of the mobile phone cover of FIG. 1;

FIG. 6 is a top plan view of the mobile phone cover of FIG. 1; FIG. 7 is a bottom plan view of the mobile phone cover of FIG. 1;

FIG. 8 is a rear perspective view of the mobile phone cover of FIG. 1; and,

FIG. 9 is a perspective view of the mobile phone cover of FIG. 1.

In FIG. 9, the evenly-segmented broken lines depict an unclaimed mobile phone to which the mobile phone cover may be docked. The alternately long- and short-segmented broken lines represent the pathway along which the cover is exploded from the unclaimed mobile phone. The broken lines and the mobile phone form no part of the claimed design.
